AIR CLEANER AND SILENCER

John J. Dreznes, Chicago, Ill., assignor to United Specialties Company, Chicago, Ill., a corporation of Delaware

Application October 8, 1949, Serial No. 120,320

5 Claims. (Cl. 183—15)

1

This invention relates to an air cleaner and, in particular, to a silencer for use with a cleaner. It has for one object to provide a silencer construction suitable for use or combination with an air cleaner. In the particular form here shown, the cleaner is suitable for attachment to an internal combustion engine and primarily for attachment to an internal combustion engine adapted to be mounted upon a vehicle. The invention is not limited to this particular association or use.

Another object is to provide an air cleaner, including a silencer, in such form that space is economized and the entire device can readily be positioned in a limited space.

Other objects will appear from time to time in the course of the specification.

The invention is illustrated more or less diagrammatically in the accompanying drawings wherein:

Figure 1 is a side elevation with parts in section illustrating one form of the device;

Figure 2 is a side elevation with parts in section illustrating a modified construction.

Like parts are indicated by like characters throughout the specification and drawings.

In the particular form here shown, the silencer is combined with an oil bath air cleaner. It might be combined with other types of cleaners and the invention is therefore not limited to the combination of the silencer with the particular type of cleaner shown.

The cleaner generally comprises an oil sump, a baffle positioned in the oil sump and initially partly below the oil level, a filter mass above the oil sump and above the baffle, means defining an inlet to the oil sump and an outlet from the filter mass. The parts thus far described comprise essentially the cleaner structure. To these are added a number of parts defining silencer means and an outlet passage member directed through the silencer means and communicating with a passage or conduit member shaped to be connected to an engine or to the intake of a carburetor which is itself connected to an engine.

The cleaner, as shown in Figure 1, comprises a sump 1. To the sump is attached an upwardly extending wall member 2 which is shaped to define a shoulder 3 and an inwardly and downwardly curved portion 4. The wall member may be provided with a plurality of inlet openings 5 at or near its upper end. The sump includes a generally tubular portion 6 shouldered at 7 and secured to an outlet tube member 8. A gasket 9 may be positioned upon the shoulder 7. A filter

mass 10 is enclosed within a shell or housing 11 which includes an inner portion 12 which forms a part of the outlet passage through which gases are conducted from the cleaner. The members 2 and 11 define an annular inlet passage for gases to enter the cleaner. The filter mass itself is supported at the bottom upon a spider 13 which may be formed integrally with the member 11 and by a screen 14a. At its upper end the filter mass is confined by a screen or a perforated member 14. At its upper end the tubular member 12 is outwardly flared, as at 15, and is provided with a downwardly directed lip 16. The filter structure is supported upon the shoulder 7 and holds in place upon that shoulder a baffle member 17.

As shown, the baffle includes a downwardly depending flange 18 and an upwardly curved portion 19 which at its inner edge rests upon the gasket 9 or upon a flange 20 formed by turning the lower edge of the tubular member 12 inwardly. Preferably the inner portion 19 of the baffle is curved to conform in shape with the portion of the filter mass housing with which it is in contact. The baffle is provided with one or more openings or louvers 21 and an inwardly and downwardly directed member 22 is formed adjacent and beneath each of the openings 21.

In the outlet passage member 8 are formed one or more openings 23. A spider 24 is fixed in the member 8, and to it is fixed an attaching rod 25. This rod is threaded at its upper end, as at 26, and receives a cover plate member 27, which member closes the upper end of the cleaner and extends over the filter mass and contacts the top of the wall member 11. A thumb nut 28 engages the threading 26 of the member 25 and serves as a means for holding the filter mass and associated parts in position. The cover plate 27 is bent, as at 29, about the upper end of the filter mass housing 11. The filter mass, its housing, the tubular member 12 and the cover plate 27 form a unit which may be removed when the thumb nut 28 is itself removed from the rod 25. The filter structure, when fastened in place as shown in Figure 1, retains in position the baffle.

Positioned beneath the cleaner and about the sump is a housing member 30 which is secured to the member 2 by welding or otherwise. An inner flange 31 formed on the member 30 is secured to the tubular member 8. The housing 30 defines an enclosed space about and beneath the lower portion of the cleaner proper. It is closed to the exterior.

A silencer, in the form here shown, is formed

2

of two members but the structure here shown might be formed of more than two members, or indeed of a single member. As shown, it comprises a lower portion 32 which has permanently fixed to it an upper portion 33. This portion is inwardly bent or shaped and contacts the wall 2, as at 34, and is permanently secured to it by welding or otherwise. The lower portion 32 is provided with an opening 35 about which may be positioned a threaded member 36. This opening provides means for attaching a bracket to support the weight of the air cleaner. Fixed to the tubular member 8 is an elbow 37. Fixed to this elbow is an outlet pipe 38. Fixed to the silencer housing, and in the form here shown to the lower portion 32 of that housing, is an outlet tubular member 39. This member, as shown, surrounds the outer end of the conduit 38 and is of greater diameter than that conduit so that an annular clearance 40 is provided between the members 38 and 39, thus providing communication between the outlet duct and the space defined by the lower silencer casing. Communication may be provided by other means. In cases where the conduit 38 must be of the same diameter as the conduit 39, the two conduits may be joined into one continuous duct, and the communication between the outer silencing chamber and the outlet conduit provided by means of openings in the wall of the conduit 38. A tubular member 41 may be secured to the part 39 and serves as a conduit through which cleaned gases leaving the cleaner are conducted to a point at which they are to be used.

In the modified form of Figure 2, the cleaner is the same as that shown in Figure 1 and described above. The parts will not be redescribed and identical parts carry identical reference numerals in both figures. However, in the form of Figure 1, the silencer structure is positioned about the lower portion of the cleaner and beneath the cleaner. In the form of Figure 2, the silencer structure is put about the upper portion of the cleaner and above the cleaner. Air entering the annular inlet formed between the walls 2 and 11 in Figure 1 is discharged finally downwardly from the cleaner while air is discharged from the cleaner of Figure 2 upwardly. For that reason, the tubular member 12 of Figure 2 does not serve as an outlet passage for cleaned gases and it is closed by a closure plug 42.

In the form of Figure 2, the cleaner proper is closed by a member 43 which serves as the bottom of the silencer structure and serves, also, as the cover plate which forms the top of the cleaner structure proper. This member is shaped to provide an annular groove 44 within which is seated a gasket 45. The upper edge of the member 11 is in contact with the gasket 45. The member 43 at its outer edge is permanently secured, as at 46, to the upper part 47 of the silencer housing which, as shown, is provided with a top portion 48. Secured to the member 43 is a tubular conduit 49 which is integral with an elbow portion 50. A spider or cross member 51 is fixed within the portion 49. Secured to the spider 51 is an attaching rod 52 which is threaded, as at 53, at its lower end. It passes through an opening in the plug 42 and receives a thumb nut 54.

Secured to the outer end of the elbow 50 is a tubular conduit member 55. 55 is a tubular conduit member secured to the silencer housing 47. As shown in Figure 2, the member 56 overlies the discharge or outer end of the member 55 and an annular clearance 57 is provided between the

parts 55 and 56. Although the annular space 57 represents a preferable means of producing communication between the outlet duct and the silencing chamber, other means of communication between these two spaces may be used. The tubular member or conduit 55 may be connected to any suitable connection by means of which gases may be discharged from the cleaner and conducted to a point of use. The cleaner construction lends itself to mounting in a variety of positions. If an elbow downwardly directed is connected to the member 56, the cleaner may be mounted above or substantially above and somewhat to the side of a carburetor.

In both forms of the device, communication is provided between the silencer and the outlet duct. This may be provided in any desired way by openings, such as the openings 23, by clearances, such as the clearances 40 and 51, or otherwise. The invention is not limited, therefore, to any particular form of, or means for, producing communication between the interior of the silencer and the outlet duct or passage through which cleaned air goes toward the point of use.

The use and operation of this invention are as follows:

The device in either form is connected to an internal combustion engine. Usually it is connected to the intake passage of a carburetor. Because of the space requirements the device has been so arranged that it occupies a minimum of space and can be put upon or connected to a downdraft carburetor without requiring a substantial space above the top of the carburetor.

When so connected air which is drawn into the engine passes through the cleaner, entering through its annular intake passage and through the openings 5 in the housing or casing 2. This air passes downwardly between the members 2 and 11 and is deflected upwardly by the baffle 17 and passes through the filter mass 10, which may be of any material or construction suitable for filtering purposes. The air moves from the filter downwardly in the form of Figure 1 through the passage 12 and finally through the member 38 to the member 41.

In the form of Figure 2 the air does not move downwardly through the passage 12, which is closed by the member 42. The air moves upwardly through the parts 49, 50 and 55 and is finally discharged into the member 56, which is connected in any desired manner to the carburetor.

The cleaner itself is not claimed herewith. In addition to the cleaner parts necessary to accomplish oil bath cleaning, the cleaners in both forms are provided with silencing means. The final outlet member from the cleaner in each form extends into a connecting member which is joined to the carburetor or to a passage which communicates with the carburetor. Thus in the form of Figure 1 the member 38 extends into the member 39 and is of less diameter than that member, so that an annular clearance space 40 is provided between the two. In the form of Figure 2 the member 55 extends into the member 56 and is of less diameter than that member, so that an annular clearance is provided between them. In each case the members which form the outlet passage from the cleaner proper pass through a resonating and silencing chamber which is formed in the form of Figure 1 about and beneath the cleaner and which is formed in the form of Figure 2 largely above the cleaner. The resonating or silencing chambers are open to the

member which is connected to the carburetor. In the form of Figure 1 this opening is the annular opening 40 and in the form of Figure 2 it is the annular opening 57.

Resonating and silencing chambers are not in themselves new as applied to air cleaners. Their manner of operation and their silencing effect are well-known. The present invention relates primarily to the arrangement of the silencing chamber with respect to the cleaner. One purpose of the invention is to provide an effective silencing means formed as a unit with an air cleaner and so shaped and dimensioned as to require a minimum of space and to permit an economical utilization of the space within which the cleaner is to be positioned.

In the form of Figure 1 there are two silencers. The member 30 defines a silencing chamber beneath the cleaner and within the larger silencing chamber which is formed by the members 32 and 33. In both forms of the device the function of the silencing chambers is to provide means for the suppression of intake noise which normally occurs when air is drawn into an engine or into the carburetor of the engine. The second silencer chamber formed by the member 30 in Figure 1 might be omitted from that form of the device.

In order to economize space and to produce a cleaner and silencing assembly which satisfies the requirements of present day automotive design, the silencer has been positioned with respect to the cleaner mechanism around and under the cleaner, as shown in Figure 1, and largely above the cleaner, as shown in Figure 2. The cleaner outlet passage members have been provided in each case with elbows positioned within the silencer chambers, and each has been provided with a final side outlet, and provision has been made around the outlet pipe for a connection between the outlet pipe and the silencer chambers. This connection comprises the space 49 in Figure 1 and the space 57 in Figure 2.

I claim:

1. In combination, means defining an air

cleaner housing, means defining a silencer chamber in axial alignment with said air cleaner housing, conduit means defining an outlet from the air cleaner housing, said conduit means including an axially disposed portion in communication with the air cleaner housing and a laterally directed terminal portion extending through the silencer chamber and having communication therewith, and a discharge member providing communication between the interior and the exterior of the silencer chamber.

2. The construction described in claim 1 wherein said discharge member includes a conduit member having an inner end portion in communication with the interior of said silencer chamber, said inner end portion being disposed in spaced telescopic relation to the terminal portion of said conduit means.

3. The construction described in claim 1 wherein the silencer chamber is of greater diameter than and partly surrounds the air cleaner housing.

4. The construction described in claim 1 wherein the silencer chamber is of greater diameter than and surrounds the lower part of the air cleaner housing.

5. The construction described in claim 1 wherein the silencer chamber is of greater diameter than the air cleaner housing and is positioned generally above the same.

JOHN J. DREZNES.
